UNITED STATES PATENT OFFICE.

JOSEPH BECKER, OF WASHINGTON, DISTRICT OF COLUMBIA, ASSIGNOR TO EASTMAN KODAK COMPANY, OF ROCHESTER, NEW YORK, A CORPORATION OF NEW YORK.

FINDER.

1,289,088.

Specification of Letters Patent.

Patented Dec. 31, 1918.

Original application filed February 17, 1905, Serial No. 246,169. Divided and this application filed December 13, 1916. Serial No. 136,684.

To all whom it may concern:

Be it known that I, JOSEPH BECKER, a citizen of the United States, residing at Washington, in the District of Columbia, have invented a new and useful Improvement in Finders, of which the following is a specification.

My present application for patent, identified for convenience of reference as Case As, 10 is Division five of my prior application Case J, Serial No. 246,169, filed February 17, 1905 (now Patent 1,210,137, issued December 26, 1916). It relates to certain features of said Case J which are separately patentable under the head of Finders.

The present specification hereinafter refers more or less specifically to my other related patent applications as follows: Case C, now Patent 1,178,476, issued April 4, 20 1916; Case G, Serial No. 110,299, filed June 5, 1902, now abandoned, in view of prior publications cited in the appended notes, but again prosecuted, for all parts thereof that are novel and patentable, in the 25 present Case As as Division five of my co-pending and above mentioned parent Case J; the said Case J, now Patent 1,210,136, issued December 26, 1916; Case Ah or division of C, now Patent 1,210,134, issued December 26, 1916; Case An, Serial No. 124,832, filed October 10, 1916, continued as, and merged in, Case Ao or Division one of J, now Patent 1,210,137, issued December 26, 1916; Case Ap or Division two of J, Serial No. 133,162, 35 filed November 24, 1916, allowed February 7, 1918; Case Aq or Division three of J, Serial No. 136,293, filed December 11, 1916, allowed March 2, 1918; Case Ar or Division four of J, Serial No. 136,428, filed December 40 12, 1916, allowed February 7, 1918.

The present invention relates mainly to the sight directing elements of the divergent lens finder with "grazed" rear sight, first disclosed by me in Figures 4 and 5 of my said Case G; then in several of the original but now canceled figures of my said Case J, which are now reproduced as Figs. 1 to 9 of my said allowed Case Aq.

As fully explained in my said Case Ah (page 1, lines 41 to 52), a finder of the di-

vergent lens type, more particularly one in which the lens is eccentric, is incomplete and inoperative unless it is provided with some special means for determining the direction of its line of sight; and this sighting means 55 should preferably be provided with adjustments adapted to produce slight angular variations in the sighting direction, so that errors of construction, principally errors in lens grinding, may easily be compensated or 60 corrected, in the finally assembled combination of camera and finder, by a simple regulation of the said sighting direction.

Three different modes of adjusting or regulating this sighting direction have already been disclosed in my said prior Cases Ah, Aq and Ar; but the present application, Case As, discloses a fourth method of adjustment which has special advantages in those forms of the finder that determine the 70 sighting direction, as in Figs. 4 and 5 of my said Case G, or as in Figs. 1 to 9 of my said Case Aq, by means of a rear non-projecting stationary sight that is formed in, or directly on, the rear or plate-holding part of the 75 camera and which is intended to be just grazed by the refracted group of finder rays that proceeds from the distant camera field, through the finder, to the observer's eye.

The rear sight, in such combinations, as 80 already explained in describing the said Figs. 5 to 9 of my said Case Aq, can easily be shifted along such sighting edge for correcting errors of centering that are parallel to the said sighting edge; but it can not conveniently be displaced in any direction that is perpendicular to such edge.

My present invention, therefore, compensates or corrects such errors of eccentricity by bodily adjustment or displacement of the 90 finder lens itself, in the transverse direction that is substantially perpendicular to the direction of the said rear sighting edge.

My four different adjustments here referred to, for correcting the direction of the 95 line of sight, may briefly be described and clearly distinguished, as follows:

My first method of adjustment or correction is most clearly disclosed in Fig. 1 of my said Case Ah, where the adjustable slant- 100

ing direction of the line of sight is determined by means of a forward virtual or image sight V'' , located centrally in the incidental group of finder rays; and the sighting direction is corrected or adjusted (as explained on page 2, lines 69 to 89, of said Case Ah) by shifting the position of this forward sight V'' in any desired direction that is substantially perpendicular to the axial vector $e' V''$. In this type of finder the refracted group beta (β) of finder rays that proceeds from the finder to the observer's eye e passes at a considerable distance above the rear part 23 of the camera.

15 My second method of adjustment or correction is disclosed in Figs. 10 and 11 of my said allowed Case Aq, where the adjustable slanting direction of the line of sight is determined by means of a fence-like rear sight 203; and the sighting direction is corrected or adjusted by longitudinally shifting the position of this fence-like rear sight 203 until it is just grazed by the refracted group 20 20 alpha (α) of rays that proceeds from the 25 finder lens to the observer's eye.

My third method of adjustment or correction is disclosed in Fig. 12 of my said allowed Case Aq, and also in my said Case Ar, where the same slanting direction of sight is 30 determined by the head of a screw 310, located centrally in the refracted group of finder rays to serve as a rear central bead sight; and the sighting direction is corrected or adjusted, by changing the position of this 35 rear central bead sight.

My fourth method of correction or adjustment, constituting the gist of the main invention claimed in the present application, Case As, provides correcting adjustment 40 in the line of sight by changing or adjusting the position of use of the finder lens. This feature proves specially valuable in combinations such as seen in Figs. 4 and 5 of my said Case G, or Figs. 1 to 9 of 45 my said Case Aq, where the finder comprises a rear sight that is absolutely fixed and that is intended to be just grazed by the refracted group of finder rays that proceeds from the distant camera field, through 50 the finder, to the observer's eye.

The present invention, therefore, consists mainly in a specially simple and effective means for adjusting or changing the position of use of the finder lens, so that a non-projecting point P' , fixed on the rear or plate-holding part of the camera, may surely be used as an arcuate rear sight for the said finder lens, in co-operation with the marked central part M' of the lens, acting as central 55 trial sight.

My invention further consists in designing the arrangement so that the depth of the finder, as measured along the internal part, $M' P'$, of the central finder ray, shall be 60 substantially equal to the depth of the cam-

era, as measured along the internal part, $M P$, of the central camera ray, so that the finder lens, rigidly connected to the camera lens, will automatically be moved with the camera lens, to suitably change the direction 70 of the finder field, whenever the camera lens is moved transversely to change the direction $P M$ of the camera field, a principle that was first fully disclosed in my said Case G as applied to the centric divergent lens 75 finder.

In the accompanying drawings:

Fig. 1 is a face view of a bellows camera with the invention applied thereto, and

Fig. 2 is a side view of the same, mounted on a tripod and sectioned sufficiently to show the inside construction of the finder parts.

The camera when opened up for use comprises a rigid L-shaped frame 20, 21. The 85 vertical member 20 of this frame serves more or less directly as the support for the sensitized plate or film, whose center is indicated at P .

The camera objective 22, whose second nodal point is indicated by M , is mounted on a lens board 23 which is adjustable vertically between grooved uprights 24, 25, whose lower ends are rigidly connected by the horizontal member 26, and this is provided with a dovetail cleat 27 adapted to slide transversely in the lens carriage proper 28.

The lens carriage proper 28 is guided by rails 29 and 30 to provide for the longitudinal displacements required in focusing.

The eccentric lens 31, here shown single, but preferably made as a doublet as in my said Case Ap, is firmly mounted in a rectangular box-like frame 32, which is provided with a tail piece 33 by means of which the finder is adjustably fastened to the lens board 23. The tail piece 33 is provided with a slot 34 for the admission of a clamp screw 35, and it also has a hole for the admission of a screw 36, which is only inserted, as a permanent fastener, after the proper adjustment of the finder lens 31 on the lens board 23 has been found.

The finder is first temporarily fastened 115 in place by screw 35 so it can be slid about and will remain where set, and the camera is mounted on a tripod as shown in Fig. 2. A distant object is then selected and the camera is placed so that the image of such object shall fall on the center P of the camera plate or film. The finder mount 32 is then raised or lowered until the same object shall appear centrally at M' in the finder lens 31 when the observer places his eye at the proper elevation to just see the bottom line of the finder field in coincidence with the upper edge of the plate holding part 20 of the camera. The screw 36 is then inserted to permanently fix the finder in 120 125 130

place and screw 35 may also be screwed home firmly.

The operator finally notches or otherwise marks the camera frame at 15, 16, just opposite his eye, in order to determine the lateral direction of the line of sight. The middle point of this notch is indicated by P'.

Co-varying finder and camera fields.

- 10 The finder could be mounted on any part of the camera front, but I have here shown it mounted directly on the board 23 to move with the objective up and down or to one side on the principle described in my said 15 prior application, Case G. The camera here shown in Figs. 1 and 2 is of the same type as that shown in Figs. 4 and 5 of the said prior application, Case G, just referred to.

In accordance with the principles of my 20 said Case G, the variable line M' P' remains constantly of very nearly the same length as the variable line M P, so that when the objective is shifted in any direction parallel with the plate, the camera field and finder 25 field are both changed in direction by equal angles. Changes in the horizontal direction are accurately equal in both fields. Changes in the vertical direction also correspond exactly enough for all purposes if the focusing 30 displacements are relatively small.

To take advantage of the more exactly operating of these changes when the lens has to be raised or lowered, the camera need only be turned so that its present horizontal 35 dimensions shall be vertical. This change might be useful even if the camera has a reversible back, as the object of the turning it is to use the more accurately working crosswise adjustment in place of the needed 40 vertical adjustment.

NOTE 1.—The geometrical and optical principles involved in the present application Case As are substantially the same as given for the centric finder in my said 45 Case G.

NOTE 2.—The invention of my said Case G, however, was substantially anticipated in the "Spido" hand camera of Gaumont, described in *La Nature*, Paris, June 17, 1899, 50 pages 41 to 42; Fig. 3 on page 41; text in the last four lines of page 41, and the first seventeen lines of page 42.

NOTE 3.—The *La Nature* description of Note 1, was reproduced in the *Scientific 55 American Supplement*, New York, November 11, 1899, page 19955, Fig. 3; last twenty-one lines of column two, and first seventeen lines of column three.

NOTE 4.—The Gaumont hand camera was 60 also described on page 140 of the *Fabre Aide Mémoire de Photographie pour 1901*, Paris, 1900.

NOTE 5.—A device also closely resembling that of my Case G is that of Gillon described, but not illustrated in the *Bulletin* 65

de la Société Française de Photographie, Paris, 1901, pages 89 and 90. Copy at the Library of Congress.

NOTE 6.—In view of documents cited in Notes 2 to 5, I do not make any broad claim 70 for directionally changing the line of sight in a finder of the divergent lens type; but, in view of the theoretical disclosures made in my said Case G, I do claim the applicability 75 of the same principle to a lens of the eccentric lens type because such applicability is not obvious, for two different reasons, to wit: first, because the direction, P' M', of the central finder ray cannot be made parallel to the direction, P M, of the central 80 camera ray; and, secondly, because the central finder ray of an eccentric lens, being no longer an axial ray of the lens, is bent by the lens, and such bend is variable with the inclination of the incidental part of such 85 ray.

NOTE 7.—The Gillon device of Note 5, or one closely resembling it, is shown and described in *La Nature*, Paris, April 20, 1901, vol. 29¹, pages 328-329; and particularly 90 Fig. 2 (-1) on page 329, with text in the last 14 lines of page 328, first 14 lines of page 329, and first 7 lines of column 2 of page 329.

NOTE 8.—The *La Nature* article of Note 7 95 is reproduced in the *Scientific American Supplement*, New York, June 8, 1901, Vol. LI, page 21274, Fig. 2 (-1) and text in column 2, lines 14 to 39.

NOTE 9.—I am aware that Clark in British 100 Patent 10,915 of June 5, 1894, describes a camera showing an objective support that may be shifted transversely in any desired direction, and that carries an eccentric lens which is alleged to be a finder lens. Clark, 105 however, shows no means whatever for determining the direction of the line of sight of this finder lens; and without such means the combination is, as pointed out above, inoperative; moreover, the Clark central 110 finder ray, indicated by a dotted line in his Fig. 2, has the incidental, or right hand, part thereof inclined at about 18 degrees, or one-fifth of a right angle, whereas, in accordance with my invention, this same incidental part (ray X M' A in my Fig. 2) should be horizontal, assuming the camera lens to be in its normal position of use or placed as shown in Fig. 2 of Clark, and in my present Fig. 2. 115

NOTE 10.—From disclosures made in my said Case G, it appears that preservation of the identity of the camera and finder fields, is perfect, both as to extent of field and direction of field, for all changes in 125 the depth, M P, of the camera, as well as for all changes in the inclination of axis, M P, on the camera plate, only when the finder lens is of infinite focal length; that is to say, only when the finder lens is a plain 130

glass plate of the same size as the camera plate; or when it is the equivalent of the open frame or window finder surrounding said plate; or, finally, when it is similar to 5 the wire frame finder seen in Figs. 1 and 10 of U. S. Patent 365,435, issued June 28, 1887, to Freeman. The Freeman specification makes no mention of this remarkable property of his wire frame finder; but a 10 geometrically more perfect form of the same type of finder, possessing all of its here referred to automatic field preserving properties, in their highest degree of perfection, was fully disclosed by Huilliard in the 15 "Bulletin de la Société Française de Photographie," Paris, 1900, pages 173 to 175, Figs. 1 and 2, (copy at the Library of Congress). My said Case G, furthermore, proves that the centric divergent lens finder, as compared 20 with the finder of Freeman or Huilliard, is much less efficient in preserving extent of field, but equally efficient in preserving direction of field.

NOTE 11.—In using adjustment 34, the operator, judging solely by the result, simply moves the lens, up or down, until he has brought the central point of the distant camera field into apparent alinement with the middle point M' of the finder window; 25 and this simple operation is entirely independent of the amount of eccentricity that may be present in the glass lens. The invention is, therefore, directly applicable, without any modification whatever, to the 30 centric finder seen in Figs. 4 and 5 of my said Case G; and claim 1 hereinafter made is, accordingly, not limited to eccentric lenses.

NOTE 12.—Where the eccentricity of the 35 finder lens is relatively large, the focusing displacements of the camera lens will, as a general rule, and in the present type of fixed rear sight finder, produce objectionable variations in the sighting direction of the 40 finder field; hence where such focusing displacements must themselves be relatively large, the eccentricity of the finder lens should not be made larger than necessary.

What I claim as my invention, and desire to secure by Letters Patent, is:—

1. The combination with a photographic camera having a finder of the divergent lens type, with a rear sight marked or formed directly on an external edge of the camera frame, lying parallel and relatively close to 55 an edge of the inclosed plate or film; of means for holding said finder lens in its position of use; and means for changing a dimension in said lens-holding means, to permit of changing the said position of use, 60 in a transverse direction that is substantially perpendicular to the said sighting edge, so that the refracted group of finder rays that proceeds from the relatively distant camera field through the said finder 65 may be moved transversely with said finder lens, and be caused to pass grazingly by the said rear sight.

2. The combination with a photographic camera comprising a plate or film-holding 70 part, and an objective holding part, and means for transversely changing the relative position of said two parts, so that the inclination of the internal part, $M'P$, of the central camera ray, may be turned from 75 its normal position with relation to the plate or film, to an abnormal or inclined position; of a finder, for said camera, comprising two parts, to wit: first, an eccentric lens mounted on the said objective holding part 80 of the camera; and, secondly, a rear sight fixed on the said plate or film-holding part of the camera; said finder lens and said rear sight being spaced to make the internal part, $M'P'$, of the central finder ray, substantially of the same length as the internal part, $M'P$, of the said central camera ray; so that any directional change produced in the said camera field, by lateral displacements of the said camera objective, shall 85 automatically, and to the same extent, be reproduced in the direction of the said finder field.

In testimony whereof, I have signed my name to this specification.

JOSEPH BECKER.
